UNITED STATES PATENT OFFICE.

BURNHAM C. STICKNEY, OF ELIZABETH, NEW JERSEY, ASSIGNOR TO UNDERWOOD
TYPEWRITER COMPANY, OF NEW YORK, N. Y., A CORPORATION OF DELAWARE.

TYPE-WRITING MACHINE.

1,227,015.

Specification of Letters Patent. Patented May 22, 1917.

Application filed August 4, 1914. Serial No. 854,920.

To all whom it may concern:

Be it known that I, BURNHAM C. STICKNEY, a citizen of the United States, residing in Elizabeth, in the county of Union and 5 State of New Jersey, have invented certain new and useful Improvements in Type-Writing Machines, of which the following is a specification.

This invention relates to type actions for 10 typewriting machines, in which the type-bars strike upon a visible side of the platen, as for instance, on the front thereof.

The object of the invention is to produce 15 a highly compact machine of this class, particularly with a view to reducing the height of the machine to permit it to be packed in a satchel or small case, for the use of travelers.

The invention is illustrated in connection 20 with a platen in which the printing line is on the front side. The types are mounted upon type-bars pivoted in an arc below the platen. The type-bars may be of the short variety, three types being preferably placed 25 upon each bar, so as to permit fewer bars to be used, and otherwise to conduce to compactness. The platen may be shifted up and down in any usual manner; although the type-bars may be shifted up and down instead of the platen; or the platen may be 30 shifted up for writing capitals, while the type-bars are shifted up for writing figures.

A further feature of the present invention 35 is the manner of mounting the keys and the connections from the keys to the type-bars, so as to add little, if any, to the height of the machine. One feature which contributes to this end is the provision of main key-levers which extend from the front to the back of 40 the machine, and at their rear portions are connected to the type-bars by forwardly extending connections. These connections may comprise bell-crank, or sub-levers, and by reason of their arrangement behind the type-bars present an advantage over prior machines, in which the bell-crank were arranged below the type-bars, and added to 45 the height of the machine. The construction may be such that the only portions that extend beneath the type-bar segment are the key levers themselves, whereby the height of 50 the machine may be substantially reduced.

The key levers are preferably connected up to the type-bars in such a manner that considerable movement of the key is used in

starting the type-bar, and that the speed of 55 the latter is accelerated when it strikes the platen. To this end, the key lever is made in elbow form, and at the bend of the elbow is pivoted upon the horizontal arm of a bell-crank, the latter having an upright arm 60 which is connected by a forwardly extending link directly to the type-bar. The key-lever comprises an arm extending upwardly from said pivot, and the upper end of said arm is pivoted to an idle link, which is so 65 related to the bell-crank that the desired acceleration of the type-bar is effected.

Another feature of the invention is an arrangement whereby the height of the machine is still further reduced; and this feature may be used in connection with other forms of key levers. The bank of key levers is placed preferably on a level higher than the middle of the type-bar system. The lowest type-bars are at the center of the type-bar system, and the middle key levers are bowed or bent considerably to one side, to form an opening or well within which said middle type-bars may lie. When any key is depressed, its key lever will descend but 80 little, if any, below the bottom of the type-bar basket, and hence material reduction may be effected in the height of the machine.

Other features and advantages will hereinafter appear.

In the accompanying drawings,

Figure 1 is a diagram to illustrate that the type-bars may be shifted up and down for securing capitals and figures.

Fig. 2 is a sectional side elevation of a 90 front-strike writing machine embodying my improvements.

Fig. 3 is a plan of the key-lever and type-bar systems, showing the well formed by bowing or bending the middle key levers to 95 permit the middle type-bars to sink below the upper edges of the key-levers.

Fig. 4 is a diagrammatic front elevation illustrating how most of the type-bars may be allowed to sink below the level of the 100 upper bank of keys.

Keys 1, which may be arranged in three banks, are preferably mounted on stems 2 rising from the front ends of levers or key-bars 3, which are in the form of elbows, each 105 comprising an upstanding arm 4 at its rear end. Each key lever is pivoted at its elbow 5 to a guide-link which may constitute

the forwardly extending arm of bell-crank 6, 7. The bell-cranks are mounted on a fixed horizontal rod 8.

These bell-cranks comprise upstanding arms 7, and at the upper end of each thereof is pivoted at 9 the rear end of a thrust link 10, which extends forwardly and is pivoted at 11 to the short arm 12 of the type-bar 13. The type-bars may be mounted in any suitable way; as for instance, they may be mounted on a fulcrum rod 14, fixed in a segment 15, and may strike rearwardly against the platen 16, which may be shiftable up and down, as indicated in dotted lines 15 at Fig. 2, to enable different types to print; three types 17 being shown on each type-bar.

At its upper end, each of the arms 4 of the key levers is pivoted at 18 to an idle or guide link 19. These idle links 19 may be shorter than the arm 6 of the bell-cranks, and may extend upwardly and forwardly from a horizontal pivot rod 20 fixed in the machine.

It will be seen that the arm 4 operates as a link between 19 and 6, and is capable of nearly parallel up and down motion upon said members 19 and 6; but, owing to the fact that the link 19 is short so that it moves in a forwardly and downwardly inclined path, the upper end of 4 swings forwardly as well as downwardly at the beginning of the down stroke of the key, whereby the front end of the key lever 3 is given a downward tip at this time, so that the key 1 descends about one-half of its stroke while the type-bar 13 is making the first one-fourth of its printing stroke, to reach the position 13^a. Fig. 2, thus affording an easy start to the key.

40 The idle or guide link 19 is so short that during the subsequent portion of the printing stroke of the key, the pivot 18 moves down in nearly a vertical path, and hence all portions of the structure 1, 2, 3 and 4 which are mounted upon the members 19 and 6 move down very nearly in parallelism, so that the speed of the key itself relatively to the speed of the type-bar is reduced; or, in other words, the speed of the type arm is 50 accelerated.

At 1^a is shown the position of the key when the type is at 13^a. At 1^b is shown the key position when the type has made one-half of its stroke as at 13^b; the key at this 55 time having made three-fourths or more of its stroke.

During the final portion of the key stroke, the path of the pivot 18 may be downwardly, and a trifle to the rear, in comparison with the downward path of the pivot 5, thereby rocking the upper portion of the arm 4 rearwardly as said arm descends and tending thereby to tip up the front portion of the key lever, and effect a 60 relative lift of the key 1, or in other words,

to retard the descent of said key, so that the proportional movement of the type-bar at this time is much more rapid than the movement of the key. The type-bar is shown at 13^c as having made three-fourths of its 70 stroke, while the key is shown at 1^c as having made three-fourths of its own stroke; and the last fourth of the stroke of the type-bar is made during a very short final movement of the key. This relative reduction in the speed of the key tends to cushion the stroke, that is, to avoid jar to the finger of the operator when the key is finally arrested by the contact of the type with the platen. At Fig. 2, the printing positions of 75 the parts are also shown in dotted lines.

The key is mounted to float upon links 6 and 19, and connection is made from the type-bar to some portion of that linkage which comprises members 6, 4 and 19. In 80 the particular construction shown, connection is made from the type-bar directly to arm 7 connected to the link 6, although the scope of the invention is not limited to that particular arrangement. The bell-crank 90 comprising the arm 7 and link 6 forms an interponent through which the movement of the key lever is transmitted to the link 10 and type-bar.

One of the features of the linkage is that 95 it comprises an upstanding arm 4 provided upon the key-lever, and that said arm is guided up and down by links, whereby the key-lever or key-bar as a whole is given an up-and-down floating movement. The type-bar is connected by a link 10 and arm 7 to one member of the linkage 6, 4, 19, whereby the up-and-down bodily movements of the key-lever are converted into forward and backward movements of the type-bar link 10. 105

As seen best at Fig. 3, the two middle key-levers in the system are bowed between their front and rear portions to form an opening, clearance or well 21, within which sink the middle type-bars 13 when in normal 110 positions; said type-bars being preferably arranged to swing down through more than 90 degrees from the printing positions, in order to make clearance for the types when in normal positions, to permit short type-bars to be used. The middle key-levers may 115

be bowed far enough to leave a clear space beneath nearly all of the types in the system, as at Fig. 3, so that as many type-bars as may be desired may lie down in the space 120 21, left by bowing said levers. The bowing of the middle levers may be carried back as far as necessary. In the present instance, it is illustrated as not carried back of the entire type-bar, since only the forward portions of the type-bars extend down in the opening, owing to the normal inclination of the type-bar forward and downward from its pivot. Each of the middle key-levers may 125 therefore comprise a forwardly and rear- 130

wardly extending key-bearing portion 3, a laterally extending portion 3^a, a rearwardly extending portion 3^b very much off-set from the main portion 3 of the lever, a lateral return portion 3^c, and a rear main portion 3^d, upon the rear end of which is formed the upstanding arm 4. Suitable guide-combs 22 may be provided for the front ends of the levers, 23 for the rear ends, and 24 for the upper ends of arms 4.

The two key-levers adjoining the middle key-levers may be bowed or bent in the same way, but the bowing need not be so much off-set from the main body of the lever. The next pair of levers may be bowed still less, and so on, the bowed portions forming a nest, as seen at Fig. 3. The outside levers need not be bowed; but at suitable points may be bent inwardly at their rear portions, as at 3^c, so that the rear portions 3^d of all the levers may be about parallel and form a system of about the same width as the system of type-bars at their fulcrums or pivots on the rod 14. The links 10 may work in substantially parallel vertical planes, as seen at Fig. 3, and owing to the described arrangement there is little or no liability of side strain or binding of any of the parts. The outside keys are off-set considerably from the rear portions of their key-levers, but this will not be an objection, owing to the fact that each key-lever moves bodily up and down throughout all portions, and is mounted upon freely moving guide links, and provided with suitable guides particularly those near the keys themselves.

The type basket 23^a may be of suitable flexible material, as customary in this art, and may be properly supported to underlie the type-bars 13, including those which extend down into the opening or well 21 in the key-lever system, as will be understood from Fig. 2.

At Fig. 1 the type system is indicated as being movable up and down to enable different types to print, the segment 15 shifting up and down bodily, together with the type-bars, in a well-known manner, the links 10 vibrating at their forward ends about the pivots 9, to accommodate the shifting movement. One of the necessary case-shifts may be effected by shifting the type-bars, and the other by shifting the platen, if desired, as will be understood by those skilled in the art.

On the usual universal bar for operating the usual letter-feeding and ribbon-feeding mechanisms, 26 are the returning levers used for the key levers.

Other solutions may be resorted to within the scope of the invention, and portions of the various components may be used without others. In this manner, thus described, my invention, I claim:

1. A type-bar action for typewriting

machines, in combination, a rearwardly-striking type-bar, a key lever having a free arm extending forwardly from its fulcrum and provided at its forward end with a key, said lever depressible throughout its length in nearly parallel planes, actuating means for said type-bar, operating means between said key lever and type-bar-actuating means, and means whereby said key lever is given a forwardly accentuating oscillatory movement about its fulcrum when its key is depressed, whereby the speed of the key relative to the speed of the type-bar is modified, to ease the initial and final portions of its stroke.

2. In a type-bar action for typewriting machines, in combination, a rearwardly-striking type-bar, a key lever having a free arm extending forwardly from its fulcrum and provided at its forward end with a key, said lever depressible throughout its length in nearly parallel planes, actuating means for said type-bar, operating means between said key lever and actuating means, and means connected with said key lever whereby the latter, when the key is depressed, is given a forwardly accentuating oscillatory movement about its fulcrum, whereby the speed of the key relative to the speed of the type-bar is modified, to ease the initial and final portions of its stroke.

3. In a type-bar action for typewriting machines, in combination, a rearwardly-striking type-bar, a key lever, means to guide the key lever and cause it to be depressed throughout its length in nearly parallel planes, the fulcrum of the lever being carried downward as the lever is depressed, actuating means for said type-bar, operating means between said key lever and type-bar-actuating means, a vertical extension for said key lever, and a link pivoted to said extension and having a fixed fulcrum, said link arranged to impart a forwardly accentuating oscillatory movement to said lever about its fulcrum during said first-mentioned movement of the lever, to ease the initial and final portions of the lever's stroke.

4. In a type-bar action for typewriting machines, in combination, a swinging type-bar, a horizontal key lever depressible throughout its length, actuating means between said lever and type-bar for operating the latter by the downward movement of the lever at its point of connection with said means, and means for oscillating said lever about said point of connection as a fulcrum coincidently with said depression of the lever, to accelerate the speed of movement of said type-bar toward the end of its stroke relatively to the speed of movement of said lever.

5. In a type-bar action for typewriting machines, in combination, a swinging type-bar, a horizontal key lever depressed

- throughout its length as the key is depressed, a bell-crank pivoted to said lever to support and guide the latter, a link connecting said bell-crank and type-bar to actuate the latter by the former, and means to impart to the key lever, during its depression, an additional tilting movement about its point of pivotal connection with the bell-crank as a fulcrum.
6. In a type-bar action for typewriting machines, in combination, a swinging type-bar, a horizontal key lever depressible throughout its length, a bell crank pivoted to said lever to support and guide the latter and actuated by the downward movement of the lever at its point of connection with the bell crank, a link connecting said bell crank and type-bar to actuate the latter by the former, and means for oscillating said key lever coincidently with its depression to accelerate the speed of movement of said type-bar toward the end of its stroke relatively to the speed of movement of said key lever.
7. In a type-bar action for typewriting machines, in combination, a swinging type-bar, a horizontal key lever depressible throughout its length, a bell crank pivoted to said lever to support and guide the latter and actuated by the downward movement of the lever at its point of connection with the bell crank, a link connecting said bell crank and type-bar to actuate the latter by the former, and pivotal means operating through a smaller arc than said bell crank, to oscillate said key lever coincidently with its depression, thereby accelerating the speed of movement of said type-bar toward the end of its stroke relatively to the speed of movement of said key lever.
8. In a typewriting machine, the combination with a platen, of a series of rearwardly striking type-bars, a series of horizontal key levers each depressible throughout its length, a series of bell cranks pivotally supporting and guiding said key levers and located behind said type-bars, means cooperating with said bell cranks to cause the key levers to be depressed throughout their length when their keys are depressed, and a series of links connecting said bell cranks and type-bars to actuate the latter by the former.
9. The combination with a system of type-bars, of a system of key levers extending back beneath the type-bars and connected thereto, said system of key levers having an opening within which some of the type-bars normally project below the upper level of the type-bars at said opening, to effect economy in the height of the machine.
10. In a front-strike writing machine, the combination with type-bars, of key levers extending rearwardly beyond the type-bars and having upstanding arms at their rear ends, said arms forming portions of link-

ages, whereby the key levers are guided up and down, each linkage comprising a bell crank pivoted to the lower rear portion of the key lever and also comprising an idle link pivoted to the upper rear portion of the key lever. 70

11. In a type-bar action for typewriting machines, a rearwardly striking type-bar, a depressible horizontal key lever having a shifting fulcrum, means for controlling and guiding the key lever to cause a bodily downward movement thereof of nearly equal extent throughout its length when the key is depressed, a link extending rearwardly from the type-bar and operable by a forward thrust thereon to actuate said type-bar, and a swinging operative connection between said key lever and link. 80

12. In a front-strike writing machine, the combination with type-bars, of depressible key levers extending rearwardly beyond the type-bars, linkages connected to the key levers and guiding them in their up and down movements, the key levers having upstanding arms at their rear ends forming portions of the linkages, and means forming an operating connection between each type-bar and its key lever and linkage. 85

13. In a front-strike writing machine, the combination with type-bars, of depressible key levers extending rearwardly beyond the type-bars, linkages connected to the key levers, and guiding them in their up and down movements, the key levers having upstanding arms at their rear ends, said arms forming portions of the linkages, each key lever being connected through its linkage to the type-bar for operating the latter. 90 100

14. In a front-strike writing machine, the combination with type-bars, of depressible key levers extending rearwardly beyond the type-bars, linkages connected to the key levers and guiding them in their up and down movements, the key levers having upstanding arms at their rear ends forming portions of the linkages, each key lever being connected through its linkage to the type-bar for operating the latter by the downward movement of the lever at a point of connection with a linkage, the key lever and linkage being so arranged that the movement of the forward end of the key lever relative to the movement at said point of connection to the linkage is comparatively great during the initial portion of the type-stroke and decreases during the type-stroke to thereby accelerate the stroke of the type-bar. 110 115

15. In a front-strike writing machine, the combination with type-bars, of depressible key levers extending rearwardly beyond the type-bars, and linkages connected to the key levers and guiding them in their up and down movements, the key levers having upstanding arms at their rear ends forming 125 130

BEST AVAILABLE COP

1,227,015

5

- portions of the linkages, each linkage comprising a bell crank, one arm of which is connected to the type-bar.
16. In a front-strike writing machine, the combination with type-bars, of depressible key levers extending rearwardly beyond the type-bars, linkages connected to the key levers and guiding them in their up and down movements, the key levers having upstanding arms at their rear ends forming portions of the linkages, means forming an operative connection between each type-bar and its key lever and linkage, and fixed guides for the upper rear portions, the lower rear portions and the front portions of the key levers.
17. In a front-strike writing machine, the combination with type-bars, of depressible key levers extending rearwardly beyond the type-bars, linkages connected to the key levers and guiding them in their up and down movements, the key levers having upstanding arms at their rear ends forming portions of the linkages, and means forming an operative connection between each type-bar and its key lever and linkage, said key-lever system having an opening for clearance, within which some of the type-bars normally lie, to economize the height of the machine.
18. In a front-strike writing machine, the combination with type-bars, of depressible key levers extending rearwardly beyond the type-bars, linkages connected to the key levers and guiding them in their up and down movements, the key levers having upstanding arms at their rear ends forming portions of the linkages, said upstanding arms being in rear of the type-bars, means forming an operative connection between each type-bar and its key lever and linkage, and fixed guides for the upper rear portions, the lower rear portions and the front portions of the key levers.
19. In a type-bar action for typewriting machines, the combination with a key lever, of a support on which the key lever is fulcrumed, said support shiftable up and down to permit the key lever to move bodily downward when the key is depressed, a type-bar, means whereby the bodily movement of the key lever is effective to actuate the type-bar, and guiding means for the key lever to cause a tilting movement thereof about its fulcrum in combination with said bodily movement, the degree of said tilting movement relative to said bodily movement being variable during the type-stroke to control the relative speed of the type-bar and key.
20. In a type-bar action for typewriting machines, the combination with a key lever and a type-bar, of an interponent on which the key lever is fulcrumed, means coöperating with said interponent to guide the key
- lever and cause said interponent to be moved downwardly at said fulcrum by the key lever when its key is depressed, and means to transmit said downward movement to the type-bar to actuate the latter, said first mentioned means arranged to cause an oscillating movement of the key lever about its fulcrum, whereby the speed of the key relative to that of the type-bar is increased during the initial portion of the type stroke, and reduced during the final portion of the type stroke.
21. In a type-bar action for typewriting machines, the combination with a key lever, of a bell-crank on one arm of which the key lever is fulcrumed, means coöperating with the bell-crank to guide the key lever and cause it to be moved bodily downward and swing the bell-crank when the key is depressed, a type-bar, and means connecting the other arm of the bell-crank to the type-bar to transmit the motion of the bell crank to the type-bar to actuate the latter.
22. In a type-bar action for typewriting machines, the combination with a key lever, of a bell-crank on one arm of which the key lever is fulcrumed, means coöperating with the bell-crank to guide the key lever and cause it to be moved bodily downward and swing the bell-crank when the key is depressed, a type-bar, and means connecting the other arm of the bell-crank to the type-bar to transmit the motion of the bell-crank to the type-bar to actuate the latter, said guiding means arranged to oscillate the key lever about its fulcrum on the bell-crank during the depression of the key lever, and thereby variably control the speed of the key relative to the type-bar.
23. In a type-bar action for typewriting machines, the combination with a type-bar, of means to actuate the type-bar comprising a key lever having a key located in front of the type-bar, said lever extending rearwardly beyond the type-bar, a support on which the key lever is fulcrumed, said support shiftable up and down to permit the key lever to be carried downward bodily when the key is depressed, said lever having at its rear end an upstanding arm, and guiding means connected to said arm and arranged to swing the arm forwardly during the initial portion of the type-stroke, whereby a tilting movement of the key lever about its fulcrum is effected in combination with its bodily downward movement, to permit a slow movement of the type-bar relatively to the key at the beginning of the type stroke.
24. In a type-bar action, for typewriting machines, the combination with a rearwardly striking type-bar, of a key located forward of the type-bar, a key bar carrying said key and extending rearwardly beyond the end of the type-bar, means to support

BEST AVAILABLE COP'

1,227,015

and guide the said key bar and cause it to be moved bodily downward when the key is depressed, a thrust link, and means to transmit said movement of the key bar to the 5 thrust link and impart a forward thrust thereto, the link being operable by said forward thrust to actuate the type-bar.

23. In a type-bar action for typewriting machines, the combination with a type-bar, 10 of a key located forward of the type-bar, a key bar carrying said key and extending rearwardly beyond the type-bar, a bell-crank having an arm to which said key bar is pivoted, said arm having an up and down 15 movement at its point of connection with the bar, means coöperating with said bell-crank to guide the key bar and cause a bodily downward movement of the bar when the key is depressed, said bell-crank comprising 20 an arm having a forward and rearward movement, and a link connecting said last-named arm with the type-bar for actuating the latter.

24. The combination with a system of 25 type-bars, of a system of key levers comprising a set of keys located in front of the type-bars, said key levers extending rearwardly beneath the type-bars and connected thereto, the inner key levers being offset laterally to provide an opening within which 30 some of the type-bars normally project, whereby the height of the space required beneath the type-bars for the key levers, is reduced, to effect economy in the height of the 35 machine.

27. The combination with a system of

type-bars arranged to swing upwardly and rearwardly to a common printing center, the type-bars normally lying in an arc with the central type-bars at a lower elevation than 40 the outlying type-bars, of a system of key levers comprising a set of keys located in front of the type-bars, said levers extending rearwardly beyond the type-bars, the inner 45 key levers being offset laterally to provide an opening in the system of levers, into which opening the inner type-bars normally project below the upper level of the key levers, to effect economy in the height of the 50 machine.

28. The combination with a system of type-bars arranged to swing upwardly and rearwardly to a common printing center, the type-bars normally lying in an arc with the central type-bars at a lower elevation than 55 the outlying type-bars, of a system of key levers comprising a set of keys located in front of the type-bars, said levers extending rearwardly beyond the type-bars, the inner key levers being offset laterally to provide 60 an opening in the system of levers, into which opening the inner type-bars normally project below the upper level of the key levers, to effect economy in the height of the 65 machine, the outlying key levers being offset inwardly to reduce the width of the system of key levers in rear of the type-bars.
